Application November 18, 1932, Serial No. 643,167

17 Claims. (Cl. 308—85)

This invention relates to lubricating devices. The invention has been more particularly worked out in connection with journal bearings for railway trucks. Railway journals are subjected to very severe usage and hard wear and it is most essential that they be adequately and sufficiently lubricated.

10 This invention has for its salient object to provide a simple, practical and efficient lubricating device that can be readily applied to standard journal bearing structures.

Another object of the invention is to provide a bearing lubricating device that will furnish a continuous flow of lubricant whenever the 15 axle or journal is rotating.

Another object of the invention is to provide a simple and practical lubricating device that will positively feed a continuous stream or film of oil or lubricant to the parts to be lubricated.

20 Another object of the invention is to provide a lubricating device having means arranged to act as a reservoir or storage means for insuring the presence of lubricant before the device starts in operation.

25 Further objects of the invention will appear from the following specification taken in connection with the drawings, which form a part of this application, and in which

Fig. 1 is a longitudinal sectional elevation of 30 the end of a car axle, journal box, and lubricating device constructed in accordance with the invention;

Fig. 2 is a transverse horizontal sectional elevation of the structure shown in Fig. 1, the 35 top of the journal box and cover plate being removed;

Fig. 3 is a transverse sectional elevation taken at right angles to Fig. 1 and showing the lubricating device in end elevation;

40 Fig. 4 is a side elevation of the shaft or axle and lubricating device mounted thereon;

Figs. 5 and 6 are vertical sectional elevations taken substantially on lines 5—5 and 6—6 of Fig. 1;

45 Fig. 7 is a vertical sectional elevation taken substantially on line 7—7 of Fig. 1;

Fig. 8 is a transverse sectional elevation taken substantially on line 8—8 of Fig. 3;

50 Fig. 9 is a longitudinal sectional elevation similar to Fig. 1 but showing a slightly different embodiment of the invention;

Fig. 10 is an end elevation of the bracket, gears and associated parts shown in Fig. 9;

55 Fig. 11 is an end elevation similar to Fig. 10

but illustrating a slightly different embodiment of the invention;

Fig. 12 is a side elevation illustrating the structure shown in Fig. 11; and

Fig. 13 is a top plan view, partly in section, showing the lubricant guiding means illustrated in Figs. 11 and 12.

The invention briefly described consists of a lubricating device adapted to conduct oil from the oil sump in the journal box to the journal or car axle. The device is preferably mounted on the end of the axle and comprises a bracket supported on the axle and having mounted thereon a gear adapted to dip into the lubricant in the sump and driven by a gear fixed through the 15 axle. Means is provided for conducting the lubricant which is squeezed out of the intermeshing gear teeth to the surface of the axle, so that the interengaging parts of the shoe mounted on the axle and the reduced end or journal 20 formed on the axle will be lubricated by a continuous stream or film of lubricant or oil.

The invention furthermore utilizes means for insuring an initial lubrication of the bearing or journal before the gear pump or lubricant supplying means starts to function.

Further details of the invention will appear from the following description.

In the form of the invention shown in the drawings, there is illustrated a car axle or shaft 30 10, having a reduced end or journal 11 formed thereon. A flange or collar 12 is formed on the end of the journal 11.

The axle extends into a journal box 13 of the usual construction, having a well or sump 14 in the bottom thereof. One end of the journal box is provided with a U-shaped channel 15 in which are positioned closure members 16 and 17. A collar or flanged ring 18 is mounted on the shaft 10 and has annular spaced webs 19 and the upper and lower members 16 and 17 have semi-circular webs 20 and 21 disposed between or interspaced with the webs 19 and surrounding the upper and lower halves of the shaft. The staggered webs 19 and 20, 21 confine and prevent escape of the lubricant.

The lower section 17 has bars 22 extending upwardly through channels or openings in the upper section 16 and provided with openings 23 arranged to receive the outer ends of slidably latches 24 which are releasably held in their latching positions by a spring 25. When the upper section is to be raised the ends of the spring are raised and the latches 24 are drawn toward each other, thus releasing them from the 55

bars 22, whereupon the upper section 16 can be raised.

The journal box has an opening 26 at the opposite end thereof which is normally closed by 5 a spring pressed cover 27 of the usual construction.

In the form of the invention illustrated in Figs. 1 to 8 inclusive a screw or stud 30 is secured to and extends beyond the journal 11. The stud 10 has a head or enlarged portion 31 at the outer end thereof and an intermediate portion 32 between the head and the journal flange or collar 12. A gear 33 is mounted on portion 32 and has a hub 34 and a stud 35 projecting from the hub and extending into the collar 12. A plate 15 36 is positioned on the hub 34 between the gear 33 and the collar. A casing 37 is mounted on the head portion 31 of the screw 30 and encloses the gear 33 and a gear 38 which meshes therewith, between the casing and the plate 36. The gear 38 is mounted on a stud 39 which in turn 20 is carried by the casing and plate.

The casing and plate are cut away or recessed, as shown at 40, at the lower ends thereof to permit the lubricant in the sump 14 to enter the teeth of the gear 38 and to be carried upwardly in a manner hereinafter described. The casing 37 has formed thereon laterally extending wings 41 and 42 which extend across the lateral edge portions of the gear 39, as shown in Fig. 8, and communicate with a crescent shaped trough 43 carried by the plate 36. The trough 43 extends beneath the collar or flange 12, as shown particularly in Figs. 1, 3 and 5, and may have formed therein grooves 44 for receiving the lubricant.

40 A bearing shoe 45 is mounted upon and rests on the upper portion of the journal 11 and is provided with a lug 46 at the outer end thereof which extends over the upper portion or top of the flange or collar 12. A pin 47 projects beyond the lug 46 and is disposed between upwardly extending lugs 48 and 49 which are formed on the upper ends of the casing 37 and plate 36 respectively. The engagement of the lugs with the pin prevents any tendency of the casing and plate to rotate with the journal.

45

The shoe 45 has an upwardly extending flange 50 at the opposed end thereof and is provided with longitudinally extending ledges 51 and 52 along the lateral edges of the shoe. The ledges are preferably grooved, as shown at 53 and 54, and these grooves communicate with upwardly inclined end grooves 55 and 56. The ends of the grooves 55 and 56 are open and are disposed adjacent the lug 46.

The bearing shoe 45 is mounted in position on the journal by means of a member 60 which rests on the shoe and has inclined end surfaces 61 and 62 which rest on the upper surface of the shoe. The shoe 45 is provided with laterally projecting lugs 65 and 66 on which are pivoted members or plates 67 and 68. The plates 67 and 68 have mounted on the lower ends thereof pockets 69 within which are housed longitudinally extending wipers 70 of absorbent material, such as felt. The wipers 70 engage the journal substantially throughout the length thereof.

70 The plates 67 and 68 are provided with extensions which are disposed outside and closely adjacent to the opposite peripheral portions of the flange or collar 12, as shown in Fig. 5. A fin or web 71 formed on the plates 67 and 68
75 rests lightly against the collar and is adapted

to intercept and deflect lubricant which is being carried upwardly by the collar, the lubricant passing through a passage 72 between the fins or webs 71 and a parallel fin 73 into a trough extension 74 which communicates with a trough 75 carried by the pivoted plates 67 and 68. The trough 75 has perforations or openings 76 and 77 which permit the lubricant to escape therefrom and to engage the felt wipers 70.

The lubricating device above described operates as follows: When the journal 11 rotates the gear 33 will also be rotated, thus causing the intermeshing gear 38 to rotate. The lubricant in the sump 14 will be picked up by the teeth of the gear 38 and will be squeezed out between the teeth of the gears 38 and 33 and be conducted by the deflecting wings 41 and 42 to the crescent shaped ledge or trough 43. From the trough it will be carried upwardly by the collar 12 and will be intercepted by one or the other of the fins or webs 71, depending on the direction of rotation of the collar. The lubricant will then pass into the trough extension 74 and thence into the trough 75 from which it will drain to the wiper 70 carried by the trough and plate 67 or 68. Particular attention is called to the fact that the wipers will be at all times saturated with lubricant and will furnish lubricant to the shaft when it is started and before the lubricant supplying and distributing mechanism is operative.

Any lubricant that is carried upwardly by the collar beyond the deflecting fins or webs 71 will be intercepted by the lug 46 and will be conducted along the bearing shoe 45 through the grooves 55 and 56 and into grooves 51 and 52. Escape of the lubricant along the shaft 10 is minimized by the ribbed ring or flanged collar 18 and the corresponding ribs carried by the closure members 16 and 17.

Thus, a continuous stream or film of oil will be fed to the journal whenever the axle is rotating. It will be understood that when the axle rotates in one direction the lubricant will be deflected by the wing or web 41 to the crescent shaped ledge and when the axle is rotated in the opposite direction, the same function will be performed by the wing or web 42. A portion of the lubricant squeezed out of the intermeshing portions of the gears will lubricate the boss 30. 45 50

In the form of the invention illustrated in Figs. 9 and 10, the lubricant is conducted from the sump to the interengaging surfaces of the shoe and the journal in a similar manner. In 55 Figs. 9 and 10 a gear 80, similar to the gear 33 is fixed to the journal 11 and meshes with a gear 81 carried by a stub shaft 82, which in turn is carried by a bracket 83. The bracket 83 is 60 pivotally mounted on a boss 84 formed on the gear 80.

A sleeve 88 is connected to the gear 81 and is mounted on the stub shaft 82 and a roller 89 is secured to one end of the sleeve. The sleeve and roller are held on the stub shaft by a head 90 on the end of the shaft 82. The sleeve 88 has radial openings 91 to permit the passage of lubricant through the sleeve to the stub shaft. The hub of the bracket 83 which is pivoted on the boss 84 is also provided with openings 93 for the purpose of permitting the lubricant to gain access to the boss 84.

In the form of the invention shown in Figs. 9 and 10, the bracket 83 is held against rotation by the bifurcated end 95 of a bolt 96 which

engages a laterally projecting web 97 formed on the bracket. The outer end of the bolt 96 serves as a securing means for the cover plate 98 of the journal box.

5 The bracket 83 has formed on its upper end above the boss 84, a curved web 100 and a vertical web or fin 101. The web 100 and fin 101 serve to deflect oil or lubricant carried upwardly by the gear 80 and as the lubricant flows 10 over the hub of the bracket, it will enter the openings 93 and lubricate the pivotal mounting of the bracket on the boss 84.

It will be obvious that as the journal 11 in Fig. 9 is rotated, the roller 90 will carry a film 15 of oil from the sump 14 to the under surface of the journal. The oil or lubricant will then be carried around the axis of rotation of the journal to the coating or interengaging surfaces of the shoe and journal. Furthermore, the lubricant will reach the coating surfaces of the sleeve 88 and stub shaft 82 and the interengaging 20 surfaces of the hub of the bracket and the boss 84.

In the form of the invention illustrated in 25 Figs. 11, 12 and 13, there is shown a bracket 110 which is mounted on a boss 30 similar to the boss shown in Fig. 1. The bracket 110 has an upwardly extending portion 111 having a slot 112 which receives a pin 113 secured to and extending 30 beyond the end of the shoe 55.

The bracket 110 has a stub shaft 140 secured to the lower end thereof, on which is mounted a gear 142 which meshes with the gear 130 secured to the end of the shaft.

35 The bracket 110 has also formed thereon or secured thereto, laterally extending diverging wings 115 and 116 which extend longitudinally of the journal and outside the periphery of the journal flange 12. The wings 115 and 116 form troughs and are provided with upwardly extending webs 118 for intercepting the lubricant carried around by the flange and causing the lubricant to be conducted along the shaft through the troughs formed by the wings and into a pan 40 120 connecting with the troughs and disposed beneath the journal 11. The portion of the pan 45 beneath the journal has vanes 121, 122 and 123 for directing the lubricant longitudinally of the shaft or journal.

50 In the form of the invention just described, the lubricant is carried upwardly from the sump by the teeth of the gear 142 and is squeezed out of the teeth as the teeth of the gear 142 mesh with the teeth of the gear 130. The lubricant which is squeezed out is caught in the troughs 55 and is intercepted by the webs 118 and is conducted beneath the shaft by the troughs and the pan 120. The shaft journal 11 then picks up the lubricant.

60 From the foregoing description it will be clear that simple, practical and efficient mechanism has been designed for use with bearings and that lubricating means such as that described will effectively feed lubricant to the interengaging 65 surfaces of the bearing at all times during the rotation of the shaft or journal.

Although certain specific embodiments of the invention have been particularly shown and described, it will be understood that the invention 70 is capable of modification and that changes in the construction and in the arrangement of the various cooperating parts may be made without departing from the spirit or scope of the invention, as expressed in the following claims.

What I claim is:

1. A lubricating device comprising a shaft to be lubricated, an oil sump, means carried by and operable by the shaft for feeding lubricant from the sump to the shaft, said means including a bracket pivotally associated with the shaft, a gear fixed to the shaft, a gear carried by the bracket and meshing with said shaft gear, said last named gear extending into the oil in the sump and feeding the oil upwardly to the intermeshing portions of the gears, a flange on the shaft and means for conducting lubricant squeezed from said gears to said flange. 5

2. In combination, a shaft, a sump, a flange on the end of the shaft, means for feeding lubricant from the sump to the flange on the shaft, said means including a pair of intermeshing gears and deflecting means adapted to direct the lubricant squeezed out from the gear teeth to the flange, and means above the shaft for deflecting the lubricant from the flange and conducting the lubricant longitudinally of the shaft. 15

3. In combination, a shaft to be lubricated, a sump, a bracket carried by the shaft, a gear 25 driven by the shaft, a gear carried by the bracket, extending into the sump and meshing with said first gear, means on the bracket, extending arcuately around a portion of the shaft, for deflecting the lubricant from the gears toward the 30 shaft, means on the shaft for conducting the lubricant upwardly, and means above the shaft for deflecting the lubricant over the shaft. 35

4. In combination, a shaft to be lubricated, a sump, a bracket pivotally carried by the shaft, a gear carried by the bracket, extending into the sump and meshing with said first gear, means on the bracket for deflecting the lubricant from the gears toward the 40 shaft, means on the shaft for conducting the lubricant upwardly, and means above the shaft for preventing the bracket from swinging on its pivot. 45

5. In combination, a shaft to be lubricated, a sump, a bracket carried by the shaft, a gear 50 driven by the shaft, a gear carried by the bracket, extending into the sump and meshing with said first gear, means on the bracket, extending arcuately around a portion of the shaft, for deflecting and conducting the lubricant from the 55 gears toward said portion of the shaft, means on the shaft for conducting the lubricant upwardly, and means coating with and disposed adjacent to the shaft for conducting the lubricant longitudinally of the shaft. 60

6. A lubricating device comprising a shaft to be lubricated, an oil sump, a casing at the end of the shaft and communicating with the sump, a pair of intermeshing gears in the casing, one of said gears extending into the sump, a flange on the shaft, means for receiving lubricant squeezed from the intermeshing portions of said gears and conducting the lubricant to said flange, and means for intercepting the lubricant carried by said flange and for conducting said lubricant 65 to the shaft. 65

7. A lubricating device comprising a shaft to be lubricated, an oil sump, a casing at the end of the shaft and communicating with the sump, 70 a pair of intermeshing gears in the casing, one of said gears extending into the sump, a flange on the shaft, means for receiving lubricant squeezed from the intermeshing portions of said gears and conducting the lubricant to said flange, 75

- deflecting means for intercepting the lubricant carried by said flange, and a trough for receiving said lubricant and conducting the lubricant along said shaft.
5. 8. A lubricating device comprising a shaft to be lubricated, an oil sump, a casing at the end of the shaft and communicating with the sump, a pair of intermeshing gears in the casing, one of said gears extending into the sump, a flange 5 on the shaft, means for receiving lubricant squeezed from the intermeshing portions of said gears and conducting the lubricant to said flange, deflecting means for intercepting the lubricant carried by said flange, a trough for receiving 10 said lubricant and conducting the lubricant along said shaft, and absorbent wiping means receiving the lubricant from said trough and engaging the shaft.
9. Lubricating mechanism for shafts comprising 20 a shaft, a shoe resting on said shaft, troughs carried by the shoe and extending along the shaft, deflecting means on the troughs for intercepting lubricant on the shaft and directing it to the troughs, absorbent wipers carried by the 25 troughs and receiving lubricant therefrom, and means for feeding lubricant from the sump to said shaft.
10. Lubricating mechanism for shafts comprising 30 a shaft, a flange on the shaft, a shoe resting on said shaft, troughs carried by the shoe and extending along the shaft, said troughs having means for deflecting lubricant from the flange to the troughs, absorbent wipers carried by the troughs and receiving lubricant therefrom, and 35 means including gearing mounted at the end of the shaft for feeding lubricant from the sump to said flange and thence to said troughs.
11. Lubricating mechanism for shafts comprising 40 a shaft, a shoe resting on said shaft, troughs pivotally carried by the shoe and extending along the shaft, absorbent wipers carried by the troughs and receiving lubricant therefrom, and means including a casing and gearing 45 in the casing mounted at the end of the shaft for feeding lubricant from the sump to said troughs.
12. Lubricating mechanism for shafts comprising 50 a shaft, a shoe resting on said shaft, troughs carried by the shoe and extending along the shaft, absorbent wipers carried by the troughs and receiving lubricant therefrom, gearing for feeding lubricant from the sump, rotating means carried by the shaft receiving lubricant from the gearing, and deflecting means for intercepting 55 lubricant on said rotating means and directing the lubricant to said troughs.
13. In combination, a shaft, a sump, a flange on the end of the shaft, means for feeding lubricant from the sump to the flange on the shaft, 5 said means including a pair of intermeshing gears and deflecting means adapted to direct the lubricant squeezed out from the gear teeth to the flange, and means extending longitudinally along the shaft for deflecting the lubricant from 10 the flange and conducting the lubricant longitudinally of the shaft.
14. In combination, a shaft, a sump, a flange on the end of the shaft, means for feeding lubricant from the sump to the flange on the shaft, 15 said means including a pair of intermeshing gears and deflecting means adapted to direct the lubricant squeezed out from the gear teeth to the flange, and means extending longitudinally along and engaging the shaft for deflecting 20 the lubricant from the flange and conducting the lubricant longitudinally of the shaft.
15. In combination, a shaft, a sump, a flange on the end of the shaft, means for feeding lubricant from the sump to the flange on the shaft, 25 said means including a pair of intermeshing gears and deflecting means adapted to direct the lubricant squeezed out from the gear teeth to the flange, and absorbent means extending longitudinally along the shaft for deflecting the lubricant 30 from the flange and conducting the lubricant longitudinally of the shaft.
16. In combination, a shaft, a sump, a flange on the end of the shaft, means for feeding lubricant from the sump to the flange on the shaft, 35 said means including a pair of intermeshing gears and deflecting means adapted to direct the lubricant squeezed out from the gear teeth to the flange, and absorbent means extending longitudinally along and engaging the shaft for deflecting 40 the lubricant from the flange and conducting the lubricant longitudinally of the shaft.
17. A lubricating device comprising a shaft to be lubricated, an oil sump, means carried by and operatable by the shaft for feeding lubricant 45 from the sump to the shaft, said means including a bracket pivotally associated with the shaft, a gear fixed to the shaft, and a gear carried by the bracket and meshing with said shaft gear, said last named gear extending into the oil in the 50 sump and feeding the oil upwardly to the intermeshing portions of the gears.

CARLOS E. PADILLA.
